UNITED STATES PATENT OFFICE.

JOHN M. CLARK, OF EL PASO, TEXAS.

AIRPLANE APPLIANCE.

Application filed October 8, 1920. Serial No. 415,685.

To all whom it may concern:

Be it known that I, JOHN M. CLARK, a citizen of the United States, residing at El Paso, in the county of El Paso and State of Texas, have invented certain new and useful Improvements in Airplane Appliances, of which the following is a specification.

This invention relates to airplanes and more particularly to a shiftable landing gear whereby a brake may be applied to the wheels without danger of the airplane "nosing over."

In the present type of airplane, the landing gear is in fixed relation with the fuselage and the center of gravity is above and slightly to the rear of the axle. Thus, in case the wheels strike an obstacle, or a landing is made in unduly soft ground, or a brake applied to the wheels the airplane has a tendency to "nose over." This tendency is due to the fact that the wheels are so positioned that they become practically the longitudinal balance point, leaving a comparatively small portion of the airplane's weight to be supported by the tail skid. Thus it will be seen that when suddenly arrested, and the center of gravity being above the axle and only slightly to the rear thereof, the moment of inertia of the plane's weight set up in a forward direction of rotation around the axle is too great to be counteracted by the weight normally borne by the tail skid, a "nosing over" is the result. To obviate this difficulty it is proposed to provide a landing gear capable of being shifted by the pilot from his seat forward from the normal, or "take-off" position. This shifts the center of gravity further to the rear of the axle putting a heavier weight upon the tail skid thus necessitating a greater moment of inertia, due to a sudden arrest of the wheels, to cause the ship to nose over. Realizing the advantages of having the wheels well forward when making a stall landing in a small, muddy or rough field and also when applying brakes it is of added importance that the present invention provides for the shifting of the landing gear to either a "take-off" or landing position or any intermediate point therebetween.

The landing gear may also be used as a means of regulating fore and aft balance as

it can be shifted forward or to the rear in flight thus assisting the pilot to correct for "nose heaviness" or "tail heaviness."

The at present preferred embodiment of my invention is found in the specification and illustrated in the accompanying drawings in which:

Fig. 1 is a side elevation of the shiftable landing gear in its normal rearward position;

Fig. 2 is a side elevation in detail of the operating gear;

Fig. 3 is a view similar to that in Fig. 1 showing more particularly the hand brake and operating means;

Fig. 4 is a bottom plan view of the landing gear showing in detail the system of cables and pulleys operating the hand brake;

Fig. 5 is an enlarged vertical cross section through one of the wheels and the brake mechanism;

Fig. 6 is an enlarged side elevation of the braking crank and operating cable;

Fig. 7 is a detail plan view of the yoke member and equalizing bar as shown in Fig. 3.

Referring to the drawings more particularly the device consists of sleeves, "A" fixedly secured to the top of each landing gear strut "X," surrounding, and in slidable relation with, rods "B" secured to the fuselage "Q" by means of members "Y."

As indicated in Fig. 1 the wheels "Z" are in correct position for "taking-off." "C" is a shaft, bracketed to two longerons just forward of the pilot's seat. On this shaft are keyed two crank members "D" one near each end and connected by the rods "E" to rear landing gear struts just below the sleeve "A." Also keyed on shaft "C" is a ratchet wheel "F" connected by a two way pawl "H" to the lever "G." The operation of the lever "G" thus effects the shifting of the landing gear to either a forward or rearward position. The landing gear may be locked in any intermediate position by the rack "V" engaging the teeth of the gear "F." After the wheels have been shifted forward it is safe to apply the brake.

As shown in Fig. 5, attached to each wheel by means of a clamping ring "J" is a grooved brake drum "I." Keyed on the axle is

crank carrier "K" connected by means of a bolt to the crank "L." A cable "N" is attached to the extreme end of the crank "L" and leads over suitable pulleys to an equalizing bar "O."

As shown more clearly in Fig. 4 a spring "T" is attached to the center of the equalizing bar "O" and keeps the cables "N" taut at all times. The bar "O" is connected to the brake lever "P" by the cables N guided by pulleys "W" and a yoke member "R" which is held taut by the spring "S" thus preventing any kinking of the cables. It is essential that each wheel shall have the same 10 brake pressure applied as will be readily seen and for this purpose the equalizing bar "O" is provided which equalizes the tension of each cable upon each brake band with respect to one another.

20 The hand brake lever "P" is pivoted just below its center and may be easily operated by the pilot while in his seat. Upon pulling the lever "P" to the rear, the crank "L," by reason of its connection with the cable "N" causes the brake band "M" which is fitted in the channeled groove of the brake drum "I" to tighten about the latter and bring the wheels to a stop.

The operation is as follows: The pilot 30 wishing to make a slow or "stall" landing because of a small or muddy field shifts his landing gear to its most forward position and as soon as the wheels start to roll on the ground the brakes may be applied thereby 35 bringing the ship to a full stop. Before taking-off, the pilot shifts the landing gear to a rearward position to avoid extreme "tail-heaviness" on the "take-off" and to avoid undue wear on and breakage of the 40 tail skid while "taxying."

It is to be noticed that an added feature of my invention is that vertical stability may be attained by shifting the weight of the landing gear towards the nose or towards the tail of the plane thus correcting 45 for "nose-heaviness" or "tail heaviness."

Having thus described my invention, I claim:

1. In combination with an aircraft fuselage, a landing gear structure therefor located in advance of the center of gravity of the craft and adapted to be slid in a fore and aft direction to a location still further forward, and means for shifting said landing gear in such direction.

2. In combination with an aircraft fuselage, a landing gear structure therefor embodying wheels and struts, guiding means on the fuselage along which the landing gear structure is slidable longitudinally of the fuselage, and means operable from the fuselage for shifting the landing gear structure.

3. In an airplane, a fuselage, a landing gear, means connecting said landing gear to said fuselage adapted to permit the land-

ing gear to be shifted longitudinally of the fuselage, said means comprising bars rigidly attached to the fuselage longitudinally thereof and sleeves carried by said landing gear adapted to surround said bars in sliding relation therewith for the purpose specified.

4. In an airplane, a fuselage, a landing gear, means connecting said landing gear to said fuselage adapted to permit the landing gear to be shifted longitudinally of the fuselage, said means comprising bars rigidly attached to the fuselage longitudinally thereof and sleeves carried by said landing gear adapted to surround said bars in sliding relation therewith for the purpose specified, and means operable from the pilot's seat for advancing or retracting the landing gear on said slideable connecting means.

5. In an airplane, a fuselage, a landing gear, means connecting said landing gear to said fuselage adapted to permit the landing gear to be shifted longitudinally of the fuselage, said means comprising bars rigidly attached to the fuselage longitudinally thereof and sleeves carried by said landing gear adapted to surround said bars in sliding relation therewith for the purpose specified, means operable from the pilot's seat for advancing or retracting the landing gear on said slideable connecting means, and means for locking the landing gear in any position to which it may be shifted.

6. In an aircraft, the combination of a fuselage, a wheeled landing gear structure, means for sliding said structure in a fore and aft direction relatively to the fuselage, and wheel brake mechanism.

7. In an aircraft, a landing gear embodying wheels, and means operable from the pilot's seat for sliding said wheels forwardly to a position well in advance of their normal supporting position.

8. In combination in an airplane, a fuselage, a landing gear, means connecting said landing gear to said fuselage adapted to permit the landing gear to be shifted longitudinally of the fuselage, said means comprising bars rigidly attached to the fuselage longitudinally thereof and sleeves carried by said landing gear adapted to surround said bars in sliding relation therewith for the purpose specified, and brake means operatively connected to said landing gear.

9. In combination in an airplane, a fuselage, a landing gear, means connecting said landing gear to said fuselage adapted to permit the landing gear to be shifted longitudinally of the fuselage, said means comprising bars rigidly attached to the fuselage longitudinally thereof and sleeves carried by said landing gear adapted to surround said bars in sliding relation therewith for the purpose specified, means operable from the pilot's seat for advancing or retracting

the landing gear on said slideable connecting means, and brake means operatively connected to said landing gear.

10. In an aircraft, a landing gear embodying wheels, means operable from the pilot's seat for shifting said wheels forwardly to a position in advance of their nor-

mal supporting position, brake mechanism including brake elements applicable to said wheels, and means for equalizing the braking pressure of said elements. ¹⁰

In testimony whereof I have affixed my signature.

JOHN M. CLARK.
